(57) CLAIM

The ornamental design for a solid cosmetic with container, as shown and described.

DESCRIPTION

1. Solid cosmetic with container

1.1 : Front

1.2 : Back

1.3 : Top

1.4 : Bottom

1.5 : Left

1.6 : Right

1.7 : Right-front perspective view

1.8 : Left-front perspective view

1.9 : Right-back perspective view

1.10 : Left-back perspective view

The broken line portions of the solid cosmetic with container are included for the purpose of illustrating the environmental structure and form no part of the claimed design.

The container is filled with a solid cosmetic, and the solid cosmetic is sold and used in the state in which it is fixed to the container; the cosmetic is used as rouge for cheek and lip, as an eyeliner, and for the eyebrows, or the like.

1 Claim, 10 Drawing Sheets
